UNITED STATES PATENT OFFICE.

FREDRICK S. MARCELLUS, OF AMSTERDAM, NEW YORK, ASSIGNOR TO GENERAL ELECTRIC COMPANY, A CORPORATION OF NEW YORK.

COMMUTATION.

Application filed October 9, 1923. Serial No. 667,575.

To all whom it may concern:

Be it known that I, FREDRICK S. MARCELLUS, a citizen of the United States, residing at Amsterdam, in the county of 5 Montgomery, State of New York, have invented certain new and useful Improvements in Commutation, of which the following is a specification.

My invention relates to a novel commutation device for dynamo electric machines and in particular for dynamo electric machines of the instrument class where variation in voltage at the commutator brushes is decidedly objectionable.

10 The well known commutation arrangement where brushes rub against the commutator is in general unsatisfactory for instrument purposes not only because of the appreciable drop in voltage between the 15 brushes and the commutator but particularly because of the variations in this so-called contact voltage under different conditions. If, in the common arrangement, the brush pressure is increased until the 20 contact voltage is constant and of an infinitesimal value under all conditions as is essential for instrument purposes the friction becomes excessive and the wear on the commutator and brushes necessitates their frequent 25 adjustment and replacement. Modifications of the well known commutation arrangement have been proposed and used to a limited extent in instrument work where the voltage of the commutated circuit is substantially constant and of a high 30 value as compared to the contact voltage and where the commutated current and speed of rotation of the commutator does not vary appreciably. The commutating 35 40 type instrument has advantages which would make its use more general if the commutation difficulties could be eliminated or materially diminished.

It is a primary object of my invention 45 to provide a commutating device in which the objections above referred to are substantially eliminated. Another object of my invention is to provide a commutating device where the contact pressure is automatically 50 varied in proportion to the speed of rotation of the commutator. Other advantages of my invention will appear as the description proceeds.

In carrying my invention into effect I 55 cut grooves in the commutator transversely

of the commutator bars preferably in the form of a worm and provide brushes therefor cut to fit the grooves in the commutator preferably in the form of worm pinions meshing with the worm cut in the commutator. These brushes are split and the parts thereof are resiliently caused to bear against opposite sides of the commutator grooves whereby greatly increased contact area between commutator and the brushes is made 60 available and whereby the brush pressure and the friction incident thereto is materially reduced. The contact thus provided is largely longitudinal instead of radial and when the arrangement is in the form of a 65 worm screw the work done by the screw increases with the speed of rotation of the commutator so that the contact pressure is proportional to the speed of rotation whereby the minimum contact pressure necessary 70 for good commutation may be automatically maintained at all speeds. In such an arrangement the direction of rotation may be reversed without affecting the brush adjustment to the slightest extent.

The features of my invention which I believe to be novel and patentable will be pointed out in the claims appended hereto. For a better understanding of my invention reference is made to the following description taken in connection with the accompanying drawings, Fig. 1 of which represents my invention applied to an electric tachometer; Fig. 2 shows an end view of the commutator and brush rigging of Fig. 1 75 and also illustrates how the pinion brush may be utilized to operate a register; Fig. 3 is a detailed sectional view of a preferred form of brush pinion; Fig. 4 is a section taken on line 4—4 of Fig. 3; and Fig. 5 80 is a modification of my invention particularly designed for high current machines.

Referring to the drawings, and more in particular to Fig. 1, I have illustrated an electric tachometer connected to measure the 85 speed of a shaft 10. The stationary field member 11 of the tachometer is represented as a permanent magnet, between the poles of which a direct current armature 12 rotates. The commutator 13 of the armature 90 100 105 110 115 120 125 130 135 140 145 150 155 160 165 170 175 180 185 190 195 200 205 210 215 220 225 230 235 240 245 250 255 260 265 270 275 280 285 290 295 300 in the usual way and the worm cut therein after assembling. The brushes 14 comprise worm pinions accurately cut to mesh with the worm on the commutator and suitably held in place in mesh with opposite diameters of the commutator. The pinions 14 are preferably made of metal such as copper or brass and are consequently of very low resistance as compared to the carbon brush 10 usually used. The carbon brush or its equivalent is desirable in the usual commutation arrangement because of its wearing and lubricating properties. In my present arrangement the brush pressure may be reduced to a very low value so that a metal pinion brush may be used, and when it is considered that metal such as pure copper has several hundred times the conductivity of pure carbon the great advantage of my invention as regards voltage drop in the brushes themselves becomes evident.

The pinion brushes 14 are mounted on suitable shafts 15 which are pivotally held in stationary frames 16 constituting the brush holders which of course are insulated from and supported by a stationary portion of the machine as is usual. The brush holders are connected by wires 17 with voltmeter 18 calibrated in speed units.

30 In an electric tachometer where friction is of no particular importance, I may provide spring conducting clips or brushes 19 between the brush holder 16 and the hub 20 of the pinion 14. This is not essential, however, since there is ample contacting surface between the bearing of shaft 15 and the metallic brush holders 16. If desired an oil wick 21 may be provided to lubricate the worm gear or the commutator and brush rigging may be enclosed in a suitable chamber and allowed to run in oil if desired.

To improve the brush contact I have found it advantageous to split the pinions 14 in half, as represented in Fig. 3 and provide a coiled spring 22 under tension between the halves of the pinion tending to rotate one-half of the pinion with respect to the other half. A suitable cavity is provided about the shaft 15 to accommodate the spring the ends of which are secured to the two halves of the pinion by bent-over portions 23 which fit into corresponding recesses. Before the pinion is placed in mesh with the worm the two halves of the pinion 55 are rotated with respect to each other to give the spring the desired tension. When the pinion is in place, the spring tends to unwind and in doing so, a corresponding tooth in the two halves of the worm pinion bears firmly against the opposite walls of the commutator groove with which it is in mesh and makes a good contact even though there should happen to be considerable acceleration and deceleration of the commutator 60 and even though the grooves may happen

to be worn somewhat wider than the teeth of the pinion. This arrangement automatically compensates for any wear which may take place and makes frequent adjustment of the brushes unnecessary. It will be noted however, that the contact pressure is adjustable by adjusting the tension of the spring 22 rather than pressing the brushes radially against the commutator as is usually the case.

With the arrangement described, it will be evident that when the commutator speed is very low, the work done by the worm in driving the pinions will be a minimum yet a liberal and excellent metal to metal contact between the voltmeter 18 and the coils of the armature 12 will be maintained. As the speed increases, the work done in turning the pinions will increase and consequently the contact pressure will increase. This work is very small in any case although if conditions make it desirable the amount of work done by the worm may be increased by increasing the pitch of the worm or increasing the tension of the spring clips 19. The increase in contact pressure with speed may be thus adjusted so that any tendency to produce a poor contact by vibration at high speed or an increase in contact voltage due to an increase of the current at high speed is automatically compensated for. I have found that with this arrangement on an electric tachometer, accurate results at all speeds are obtained. The pointer of the voltmeter does not fluctuate at very low speeds or at very high speeds as is the case with the usual form of electric tachometer, but gives a true, steady deflection at all speeds so that the actual speed of the shaft 10 may be observed over the entire deflection range of the voltmeter.

The friction of this type of commutation arrangement is considerably less than the usual arrangement for equal conditions of speed and the value of current commutators. There is no chance for poor contact due to the brushes sticking. Dirt particles do not affect the commutation to the same extent as in the usual arrangements. The contacting surfaces are kept bright and polished due to the continuous rotation of the parts and the contacting surface of the brushes is continually changing, thus evenly distributing the wear and assuring long life. The heat radiating capacity of both the commutator and the brushes is materially increased over the usual arrangement, which is a decided advantage where large currents are to be commutated. Sparking due to brush vibration is entirely eliminated.

For electric meter work where a substantially constant voltage circuit is to be commutated and where the meter speed does not vary materially and is of constant direction, the pitch of the worm gear may be reduced

to zero and the spring clips 19 may be eliminated to decrease the friction to a negligible value. It will be an advantage, however, to retain the worm screw feature of the 5 brushes since then I may operate the meter register from one of the pinions 14, as I have illustrated in Fig. 2 at 24. The extension 25 of shaft 15 between the brush holder and register will preferably be made 10 of insulating material. On the tachometer the register may be calibrated to give the number of rotations of the shaft 10. The worm screw feature is also advantageous for 15 meter work since it will tend to make the brush friction loss more nearly proportional to the other losses which increase with the load, giving a better load curve for the instrument.

In Fig. 1, I have represented an electric 20 circuit 26 containing a shunt 27. The shunt leads may be connected to the brushes of the commutator machine by means of the switch 28 and the shaft 10 disconnected, thus representing the application of my invention 25 to an ampere hour meter.

I do not wish to limit my invention to electric meter work nor to the particular modification shown and described as it will be evident that the advantages of high 30 conductivity of the brushes, a good contact under all conditions of speed and direction of rotation, the liberal heat radiating surface of the brushes and commutator and the long wearing features of my improved type 35 of commutation device will be advantageous in large dynamo electric machines such as power motors and generators.

In Fig. 5 I have illustrated a modification 40 of my invention particularly applicable to machines of the last mentioned class where large currents are to be commutated. The commutator 30 is grooved but instead of using a worm thread, thrust collars 31 merely wave back and forth slightly in order 45 to give the brush 32, constructed in the form of a rack, a slight reciprocating motion. If this modification is used with a machine having the usual end play, the reciprocating motion will exist without the necessity of having the thrust collars 31 50 wave back and forth. The rack 32 may be split lengthwise and provided with a spring 33 between the sections analogous to the spring 22 of Fig. 4, tending to move one section 55 lengthwise with respect to the adjacent section to assure contact on both sides of

the thrust collars and the rack teeth under all conditions. A suitable stationary guide and support 34 is provided through which the brush rack 32 may slide and the outer end 60 of the rack may be extended to accommodate current leads 35 preferably one for each section of the rack. In this modification, the contacting surface is materially increased over the usual carbon brush contact 65 for the same width of brush. The advantageous features of metal to metal contact, the increased heat radiating surface, the automatic brush adjustment for wear, the increase of contact pressure with speed and the 70 reversibility of the direction of rotation of the commutator without changing the adjustment of the brushes, are retained and I intend to cover such modification in certain of the claims appended hereto. 75

What I claim as new and desire to secure by Letters Patent of the United States, is:

1. A commutating arrangement for dynamo electric machines comprising a circumferentially grooved commutator and brushes bearing thereon cut to fit said grooves, said brushes having relatively movable sections fitting into the same groove and resilient means for causing said sections to press against opposite sides of said groove. 80

2. A dynamo electric machine of the commutator type, means mechanically driven from said machine by a worm and pinion gearing, said worm constituting a commutator for said machine and said pinion constituting a brush for such commutator. 85

3. A brush for a commutator type dynamo electric machine comprising a pinion gear split at right angles to its axis and provided with resilient means tending to 90 rotate the sections of said pinion with respect to each other about said axis.

4. A brush for a commutator type dynamo electric machine comprising a pinion gear split at right angles to its axis and provided with adjustable means tending to rotate the sections of said pinions with respect to each other about said axis. 100

5. A commutating device comprising a grooved commutator, rotatably mounted 105 brushes meshing with the commutator groove and resilient means for producing lateral as distinguished from radial contact between said brushes and groove.

In witness whereof, I have hereunto set 110 my hand this 8th day of October, 1923.

FREDRICK S. MARCELLUS.
